UNITED STATES PATENT OFFICE.

FREDERICK HART, OF POUGHKEEPSIE, NEW YORK, ASSIGNOR TO RICHARD A. JONAS
AND CHARLES S. JONAS, OF NEW YORK, N. Y.

PERFORATING-MACHINE.

1,160,885.

Specification of Letters Patent. Patented Nov. 16, 1915.

Application filed June 24, 1914. Serial No. 846,984.

To all whom it may concern:

Be it known that I, FREDERICK HART, a subject of the King of Great Britain, residing at Poughkeepsie, in the county of Dutchess and State of New York, have invented a new and useful Improvement in Perforating-Machines, of which the following is a specification.

This invention relates more particularly to machines for perforating sheets of paper or other material with lines of perforations extending across the sheets at predetermined distances apart, as, for instance, in sheets which are used for check books containing on each sheet several checks separated by lines of perforations. The invention is not, however, necessarily restricted to perforating machines but is applicable also to other machines of an analogous nature provided with punches or other tools for performing operations at predetermined points on the sheets.

The objects of the invention are to produce an efficient and desirable semi-automatic machine which can be manufactured at a moderate price and which is capable of rapid operation and can be quickly and conveniently set to operate upon sheets of different sizes, or to perform the operations in different desired positions on the sheets.

Briefly stated, the machine comprises a mechanism provided with punches, needles or other tools which operate upon the sheets, a feed device which is moved by hand to feed the sheets to the perforating mechanism, and gages movable with the feed device which control the actuation of the perforating mechanism and are adjustable so as to cause the perforations or other operations to be performed in any desired relation on the sheets.

In the accompanying drawings, consisting of six sheets: Figure 1 is a side elevation of a perforating machine embodying the invention. Fig. 2 is a plan view thereof. Fig. 3 is a rear elevation thereof, partly in section in line 3—3, Fig. 1. Figs. 4 and 5 are fragmentary longitudinal sectional elevations thereof in lines 4—4 and 5—5, respectively, Fig. 3. Fig. 6 is a fragmentary plan view, enlarged, of the sheet feed device detached. Fig. 7 is an enlarged sectional elevation thereof in line 7—7, Fig. 6. Fig. 8

is an enlarged sectional elevation thereof showing one of the gage devices. Fig. 9 is a sectional plan view in line 9—9, Fig. 8. Fig. 10 is a fragmentary sectional plan view, on an enlarged scale, of the machine in line 10—10, Fig. 3. Fig. 11 is a fragmentary transverse sectional elevation thereof in line 11—11, Fig. 10. Fig. 12 is a fragmentary side elevation thereof partly in section in line 12—12, Fig. 11, showing the position of the parts when the punch is raised. Figs. 13 and 14 are similar views showing successive different positions of the stop means for the feed device. Fig. 15 is a transverse sectional elevation in line 15—15, Fig. 12. Fig. 16 is a fragmentary plan view showing a perforating machine of slightly modified construction. Fig. 17 is a rear elevation, partly in section, thereof.

The main frame A of the machine may be of any suitable construction, that shown consisting of an upright transverse skeleton casting supported on horizontal feet a, and horizontal brackets or arms a' and a² which extend respectively forwardly and rearwardly from the upright frame. The mechanism for perforating or otherwise operating on the sheets may also be of any suitable construction, as the desired style of work or other considerations may require. The perforating mechanism shown in the drawings is constructed as follows:

B represents a vertically-reciprocating cross head extending transversely in the machine and provided at its lower side with punches, needles or other tools b for operating upon the sheets.

B' represents a bed plate arranged beneath the cross head and provided, if necessary, with a die-plate b' having perforations which the punches enter. The cross head slides on upright guide posts b² secured to the side portions of the main frame, and is reciprocated from a horizontal shaft C which is suitably journaled on the main frame and is provided at its ends with cranks or eccentrics c which are connected by pitmans c' to the ends of the cross-head. This crank shaft is normally stationary but is coupled to and uncoupled from a continuously rotating pulley D sleeved on the crank shaft by a clutch and actuating mechanism therefor which are controlled by the gages

on the feed device, as hereinafter described, so that the crank shaft makes one revolution and reciprocates the cross-head once each time one of the gages operates the controlling device of the clutch actuating mechanism. The pulley D may be driven by an electric motor d connected by a belt d' to the pulley D, or in any other suitable way.

E represents a feed table which is supported, in front of the reciprocating cross-head B, on the front frame-brackets a'. The frame bracket a' at the right-hand side of the machine preferably extends up at the side of the feed table so as to be flush with the upper surface thereof.

F represents a feed bar or device which extends transversely across and is slidable forwardly and rearwardly on the feed table. The sheets are laid on the feed table against the rear edge of this feed bar and the latter is shoved rearwardly by hand to advance the sheets to the perforating mechanism. In the construction shown in Figs. 1-15, the feed bar F consists of a flat sheet metal strip having an upturned front edge and a raised rib f formed by a channel-shaped bar secured on the flat metal strip. The feed bar is rigidly secured at one end to a guide bar f' which extends forwardly and rearwardly of the machine and is arranged to slide in a guide groove f² in the adjacent front and rear frame-brackets a' and a². f³ is a gage for the side edges of the sheets which is adjustable transversely of the machine on the feed bar as may be required to accommodate sheets of different widths. As shown in Fig. 7, the side gage f³ is slotted to slidably fit the channel rib f of the feed bar and is provided with a thumb-screw f⁴ for pinching the upper flange of the rib f in the slot of the gage to secure the gage in the position to which it is adjusted. The side gage is retained perpendicular to the feed bar by a shoulder f⁵, Fig. 7, at the rear end of the gage sliding against the rear edge of the feed bar. The feed device can be of any other suitable construction.

G, G', G², G³ represent the gages which control the operation of the perforating mechanism. These gages are connected one in advance of the other, to the feed device, so that when the latter is moved rearwardly in feeding the sheets to the perforating mechanism the gages will move therewith and successively actuate a controlling device H for the perforating mechanism and cause the intermittent operation thereof. Any number of gages may be used, depending upon the number of lines of perforations which it is desired to make in a sheet, and the gages are adjustable to different positions relative to the feed bar to enable any desired location of the lines of perforations in the sheet. The gages may be constructed and adjustably secured to the feed device in

any suitable way. In the construction shown in the drawings (see Figs. 6-10), each gage consists of a block g which is adjustably secured on the guide bar f' of the feed device, and a finger g' which is pivoted to g and projects laterally from the block g. The block g is adjustably secured by a clamp bolt g² having a head seated in an undercut groove g³ in the guide bar, and a nut g⁴ on the upper end of the bolt. A spring g⁵ holds the finger g' against a stop g⁶ whereby the finger is adapted to yield and pass by the controlling device H when the feed device is pulled forwardly, but is held rigid with the block g and adapted to engage and move the controlling device H when the feed device is moved rearwardly with the sheet to be perforated.

The gages can be conveniently placed in the proper position by marking on a sheet the points where the lines of perforations are to be made, then placing the sheet on the feed table against a setting block or gage g⁷ on the feed bar, as indicated by dotted lines in Fig. 6, and adjusting the gages G-G³ on the guide bar f' with their rear ends registering with the marks on the sheet. The setting gage g⁷ is so located with reference to the rear edge of the rib f of the feed bar F that when the sheet is placed against this edge to be fed to the perforating mechanism the points marked on the sheet will be located beneath the punches when the controlling device H is actuated by the respective gages G-G³ to cause the operation of the perforating mechanism.

The controlling device H is operatively connected to the clutch mechanism which connects the crank shaft C for the perforating mechanism with its drive pulley D, and each time the controlling device is moved by one of the gages the clutch mechanism is operated to cause one revolution of the crank shaft and one reciprocation of the cross-head B. In the construction shown, the controlling device consists of a plate or lever which is pivoted in the frame-bracket a' at the outer side of the guide bar f' and has an inclined upper face which normally projects up into the path of the fingers g' of the gages G-G³, so that as each gage is moved past the controlling device H its finger g' will engage and depress the controlling device. The movement of the controlling device is transmitted by a push rod h to a lever h', see Fig. 3, which is connected by a link h² to a trip lever h³ for the clutch mechanism. The controlling device H and the push rod h are preferably located in recesses in the outer side of the frame-bracket a', in which they are retained by a removable cover-plate h⁴ and the levers h' and h³ are suitably fulcrumed on the main frame with the trip lever h³ extending into proximity to the clutch mechanism. A spring h⁵, Fig. 130

12, connected to the trip lever, acts to return the controlling device H to the normal raised position shown in Fig. 12, after it has been depressed by one of the gages G—G³, and hold it yieldingly in this position.

Any suitable clutch mechanism may be employed which when tripped, will connect the crank shaft C of the perforating mechanism to the drive pulley D and automatically release it after one complete revolution. The clutch mechanism shown in the drawings (see Fig. 3) is the same as that disclosed in Patent No. 828,546, granted August 14, 1906, to myself, assignor to R. A. & C. S. Jonas, and is only illustrated and described herein sufficiently to enable an understanding of its operation.

I represents a clutch member which is slidably mounted on the crank shaft C so as to turn therewith, and is adapted to interlock with a coöperating clutch member I' formed on or secured to the pulley D.

i represents a latch-tripping finger which swings from one arm of the trip lever h³ and has a hook at its lower end adapted to engage under a shoulder on a latch i'.

In the normal or rest position the sliding clutch member I is held out of engagement with the coöperating clutch member against the action of a spring i² by a stronger spring i³ which connects the upper ends of a clutch shifting lever i⁴ and a safety lever i⁵, and the parts occupy the position shown in Fig. 3, a detent i⁶ being held by the latch i' against a lug i⁷ on the hub of the sliding clutch member I and pressing the lug against the inclined face of a lug i⁸ on the safety lever i⁵. When the trip lever h³ is rocked by the depression of the controlling device H, the trip finger i is lowered, and when the controlling device and trip lever h³ are returned by the spring h⁵ the trip finger engages and lifts the latch i'. The sliding clutch member I is now moved by its spring i² into engagement with the coöperating clutch member, and rotates the crank shaft, thus carrying the lug i⁷ away from the detent i⁶. The detent is then pressed out by a spring i⁹ and the latch again drops into engagement with the detent. When the lug i⁷ comes around into engagement with the beveled face i¹⁰ of the detent i⁶ it and the clutch member are moved over against a stationary projection i¹¹ on the frame, and as soon as the lug i⁷ passes this projection i¹¹ the spring i³ suddenly pulls the shifting lever i⁴ and throws the sliding clutch member out of engagement with the other clutch member, the parts then being again in the rest position. The engagement of the lug i⁷ with the lug on the safety lever prevents any over movement of the crank shaft C. Thus the crank shaft makes one revolution and lowers and raises the cross head of the perforating mechanism each time the controlling device H is depressed by one of the gages G—G³.

K represents a stop device or abutment adapted to engage the gages G—G³ for arresting the feed device F at the points necessary to properly locate the lines of perforations and preventing the feed device from being moved during the operation of the perforating mechanism until after the punches have been withdrawn from the sheet. This stop device, in the construction shown (see Figs. 12-14), consists of a plunger arranged to slide vertically in the frame-bracket a' in rear of the controlling device H, and a spring-actuated latch L adapted to engage a shoulder k on the plunger and hold it down out of the path of the gages G—G³ against the action of a lifting spring h'. The plunger K and latch L, as shown, are confined in guide grooves in the frame-bracket a' by the cover plate h⁴. The latch L is held by its spring l in engagement with the shoulder of the plunger K and holds the plunger in its normal depressed position shown in Fig. 12, and is retracted to release the plunger by an arm l' on the controlling device H which extends into a notch l' in the latch. When the controlling device H is depressed by one of the gages G—G³, it retracts the latch L and the plunger K is raised by its spring h' to the position shown in Fig. 13, in which the gage is adapted to strike the plunger and arrest the movement of the feed device F. The gage is arrested by the plunger K just after it passes by the controlling device so that the feed device is arrested before the cross head B descends. When the cross head descends, a push rod M carried thereon above the plunger K, engages and depresses the plunger, as shown in Fig. 14, and when the gage clears the controlling device and permits it to be returned to the normal raised position the latch L is moved by its spring into engagement with the plunger and holds the same down. The plunger is held down during the upward movement of the cross head, but the push rod M is at this time in front of the gage as shown in Fig. 14, and blocks the movement of the gage and feed device until the cross head has ascended far enough to raise the push rod from in front of the gage. The punches will then have been withdrawn from the perforations in the sheets. As shown, the push rod M is arranged to slide in a vertical hole in the cross head in which it is retained by a pin m working in a slot m', and is pressed downwardly by a spring m² which is strong enough to overcome the lifting action of the spring h' for the stop plunger. The push rod is thus adapted to depress the plunger when the cross head descends but it can yield and thus prevent injury to the machine in case one of the gages or any

other object should happen to be beneath the push rod when the cross head descends.

The stop means just described enable the feed device to be moved quickly in feeding the sheets and insure of the same being arrested and held stationary at the proper points during each operation of the perforating mechanism without requiring special attention or skill on the part of the operative. Furthermore, the stop means prevent the sheets from being torn by the movement of the same while the punches are in engagement with the sheets.

N represents a driven roller arranged transversely of the machine in rear of the bed plate B' in position for the sheets to pass over the same as they leave the perforating mechanism. The roller can be driven by a crossed belt n connecting it with the driving pulley D or by other suitable means. In feeding the sheets to the perforating mechanism the operative holds the sheet against the feed bar with his fingers. When the last line of perforations has been punched he releases the sheet by lifting his fingers and the roller N then discharges the sheet onto a receiving table or receptacle O, Fig. 1, at the rear of the machine.

The machine shown in Figs. 16 and 17 is substantially the same as above described except that the clutch mechanism for connecting the operating crank shaft C of the perforating mechanism to the drive pulley D is also controlled by an additional set of gages on a guide bar secured to the opposite end of the feed bar F.

P represents the additional guide bar and Q, Q', Q² the gages thereon. The guide bar P can be constructed and guided and the gages constructed and adjustably secured thereto in the same manner as before described in connection with guide bar f' and the gages G—G². The provision of the additional set of gages enables the gages on one guide bar to be set in staggered relation to the gages on the other guide bar. In this way the gages can be set to locate the lines of perforations in the sheets closer together than is possible with only one set of gages on one guide bar, since with a single set of gages the lines of perforations cannot be located closer together than the length of one gage. The gages Q—Q² actuate a second controlling device R, similar to the controlling device H, located in their path of movement, and this controlling device R may act through any suitable connections to trip the clutch mechanism for the crank shaft C. As shown, the controlling device is connected by a push rod r, lever r' and link r² to a second trip lever r³ which is located beside the trip lever h² and has a swinging trip finger r⁴ adapted to trip the clutch latch in the same manner as the other trip device described. In this construction the gages of

the two sets will operate alternately or otherwise, depending upon the relative adjustment of the gages on the guide bars.

While the machine is especially designed for perforating sheets of paper and other light material, it is obvious that it might be applied to other purposes by providing the cross-head with tools appropriate for effecting the desired operation.

I claim as my invention:

1. The combination of a tool for operating upon the sheets, a manually operated feed device for moving the sheets past the tool, mechanism for operating said tool, driving means for the same, gages which are connected with said feed device to move therewith, and means controlled by said gages for intermittently connecting said driving means with said tool-operating mechanism. 75

2. The combination of a tool for operating upon the sheets, a reciprocating feed device for moving the sheets past the tool, mechanism for operating said tool, driving means for the same, gages which are connected to and move with said feed device, and means controlled by said gages for intermittently connecting said driving means with said tool-operating mechanism. 80

3. The combination of a tool for operating upon the sheets, a feed device for moving the sheets past the tool, mechanism for operating said tool, driving means for the same, gages which move correspondingly with said feed device and are adjustable in the direction of movement of the feed device to different positions relative thereto, and means controlled by said gages for intermittently connecting said driving means with said tool-operating mechanism. 85

4. The combination of a tool for operating upon the sheets, a feed device for moving the sheets past the tool, mechanism for operating said tool, driving means for the same, gages which are connected with said feed device to move therewith and are adjustable to different positions relative to the feed device, a controlling device which is actuated by said gages, and means which are set in operation by said controlling device for intermittently connecting said driving means with said tool-operating mechanism. 95

5. The combination of a tool for operating upon the sheets, a feed device for moving the sheets past the tool, mechanism for operating said tool, driving means for the same, gages which are connected one behind the other with said feeding device to move therewith, a controlling device which is arranged in the path of and is actuated by said gages in succession, and means controlled by said controlling device for connecting said driving means with said tool-operating mechanism. 100

6. The combination of a tool for operating upon the sheets, a feed device for mov- 105

ing the sheets past the tool, mechanism for operating said tool, driving means for the same, gages which are secured one behind the other to said feed device and are adjust-
 5 able to vary the distance between the same, a controlling device which is arranged in the path of and is actuated by said gages in succession, and means controlled by said controlling device for connecting said driv-
 10 ing means with said tool operating mechanism.

7. The combination of a tool for operating upon the sheets, a hand actuated slide-
 15 able feed device for moving the sheets past the tool, mechanism for operating said tool, driving means for the same, gages which move with said feed device, and means controlled by said gages for intermittently connecting said driving means with said tool-
 20 operating mechanism.

8. The combination of a tool for operating upon the sheets, a feed table on which the sheets are placed, a feed device for the sheets mounted to slide over said feed table
 25 toward and from said tool, mechanism for operating said tool, driving means for the same, gages which move with said feed device, and means controlled by said gages for intermittently connecting said driving
 30 means with said tool-operating mechanism.

9. The combination of a tool for operating upon the sheets, a feed device for moving the sheets past the tool, a gage which moves with said feed device, mechanism con-
 35 trolled by said gage for operating said tool, and a stop device which prevents the movement of said feed device during the operation of said tool.

10. The combination of a tool for operating upon the sheets, a feed device for moving the sheets past the tool, a gage which moves with said feed device, mechanism controlled by said gage for operating said tool, and a stop device which intercepts said gage
 45 and prevents the movement of said feed device during the operation of said tool.

11. The combination of a tool for operating upon the sheets, a feed device for moving the sheets past the tool, gages which move with said feed device, mechanism controlled by said gages for intermittently operating said tool, and a stop device which intercepts said gages in succession for preventing the movement of said feed device
 55 during the operation of said tool.

12. The combination of a tool for operating upon the sheets, a feed device for moving the sheets past the tool, a gage which moves with said feed device, mechanism controlled by said gage for operating said tool, a stop device, and means also controlled by said gage for moving said stop device to a position to prevent the movement of said feed device during the operation of said
 60 tool.

13. The combination of a tool for operating upon the sheets, a feed device for moving the sheets past the tool, a gage which moves with said feed device, mechanism for operating said tool, a stop device, and means controlled by said gage for moving said stop device to a position to prevent the movement of said feed device during the operation of said tool.

14. The combination of a tool for operating upon the sheets, a feed device for moving the sheets past the tool, a gage which moves with said feed device, mechanism for operating said tool, a stop device, means controlled by said gage for moving said stop device to a position to prevent the movement of said feed device during the operation of said tool, and means for returning said stop device.

15. The combination of a tool for operating upon the sheets, a feed device for moving the sheets past the tool, a gage which moves with said feed device, mechanism for operating said tool, a stop device, means controlled by said gage for moving said stop device to a position to prevent the movement of said feed device during the operation of said tool, and means actuated by said tool-operating mechanism for returning said stop device.

16. The combination of a tool for operating upon the sheets, a feed device for moving the sheets past said tool, mechanism for reciprocating said tool, a gage which moves with said feed device, a stop device, means controlled by said gage for moving said stop device to a position to prevent the movement of said feed device during the descent of said tool, and a device which reciprocates with said tool for moving said stop device out of stopping position.

17. The combination of a tool for operating upon the sheets, a feed device for moving the sheets past said tool, mechanism for reciprocating said tool, a gage which moves with said feed device, a stop plunger, means controlled by said gage for moving said plunger to a position to prevent the movement of said feed device during the descent of said tool, and a push rod which reciprocates with said tool and moves said plunger out of stopping position and prevents the movement of said feed device during the ascent of said tool.

18. The combination of a tool for operating upon the sheets, a feed device for moving the sheets past the tool, a gage which moves with said feed device, a controlling device which is actuated by said gage, mechanism controlled by said controlling device for operating said tool, a stop device, a spring for moving said stop device to a position to intercept said gage, a latch which holds said stop device against the action of said spring and is actuated by

said controlling device to release said stop device, and means for returning said stop device.

19. The combination of a tool for operating upon the sheets, a feed device for moving the sheets past the tool, a gage which moves with said feed device, a controlling device and a stop device arranged one in advance of the other in the path of movement of said gage, mechanism controlled by said controlling device for operating said tool, means controlled by said controlling device for moving said stop device to a position to intercept said gage after it passes said controlling device, and means for returning said stop device.

20. The combination of a tool for operating upon the sheets, a feed table on which the sheets are placed, a feed bar which extends transversely of the machine over the table, a longitudinally extending guide bar to which said feed bar is fixed, a guide at one side of said table on which said guide bar slides, gages secured to said guide bar, and mechanism controlled by said gages for intermittently operating said tool.

21. The combination of a tool for operating upon the sheets, a feed table on which the sheets are placed, a feed bar which extends transversely of the machine over the table, guide bars for said feed bar secured to the opposite ends of said feed bar and extending at right angles thereto, gages secured to said guide bars, and mechanism controlled by said gages for intermittently operating said tool.

22. The combination of a tool for operating upon the sheets, a feed table on which the sheets are placed, a feed bar which extends transversely of the machine over the

table and is movable toward said tool, two bars secured to said feed bar and extending in the direction of movement of the feed bar, a gage secured to each of said two bars, a controlling device arranged to be actuated by each of said gages, and mechanism controlled by said gages for intermittently operating said tool.

23. The combination of a tool for operating upon the sheets, a feed table on which the sheets are placed, a feed bar which extends transversely of the machine over the table and is movable toward said tool, a gage-supporting bar secured to said feed bar and extending in the direction of movement of said feed bar, gages secured to said gage-supporting bar, mechanism controlled by said gages for intermittently operating said tool, and a side gage for the sheets adjustable lengthwise on said feed bar.

24. The combination of a tool for operating upon the sheets, a feed table on which the sheets are placed, a feed bar which extends transversely of the machine over the table and is movable toward said tool, a gage-supporting bar secured to said feed bar and extending in the direction of movement of said feed bar, gages adjustably secured to said gage-supporting bar, mechanism controlled by said gages for intermittently operating said tool, and a part on said feed bar against which the sheets are adapted to be placed for adjusting said gages to cause the tool to operate at a predetermined point on the sheets.

Witness my hand, this 10th day of June, 1914.

FREDERICK HART.
